[57] CLAIM

The ornamental design for a peritoneal dialysis machine, as shown and described.

DESCRIPTION

FIG. 1 is a perspective view of a peritoneal dialysis machine showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and

FIG. 7 is a bottom plan view thereof.

FIG. 1**FIG. 2**

FIG. 3

FIG. 4

FIG. 5

FIG. 6**FIG. 7**
